UNITED STATES PATENT OFFICE.

FRED L. MACKENZIE, OF BEVERLY, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

1,403,511.

Specification of Letters Patent. Patented Jan. 17, 1922.

Application filed June 3, 1918. Serial No. 237,929.

To all whom it may concern:

Be it known that I, FRED L. MACKENZIE, a citizen of the United States, residing at Beverly, in the county of Essex and State of 5 Massachusetts, have invented certain Improvements in Fastening-Inserting Machines, of which the following description, in connection with the accompanying drawings, is a specification, like reference characters on the drawings indicating like parts in the several figures.

This invention relates to machines for inserting fastenings and has for its object improving the organization of such machines better to adapt them for operating upon work of varying characteristics.

The invention will be hereinafter described, by way of example, as applied to a machine for inserting nails from a nail 20 string of the type disclosed in the application of George Goddu and Fred L. Mackenzie, Serial No. 137,571, filed December 18, 1916. Such machine comprises a driver for the nails, which are severed one by one from 25 a nail string, an awl which penetrates the work thus forming openings in the work to receive the nails and is moved laterally while in the work to feed the work relatively to the line of drive of the nails, and a horn 30 which supports the work for operation thereon by the driver and awl and clamps it normally against the foot plate of the machine. The horn is lowered intermittently for brief intervals to unclamp the work and 35 to permit it to be fed by the awl. The work positioning mechanism of such machines commonly comprises a gage which contacts with the edge of the work adjacent to the point of penetration of the work by the awl 40 and is mounted for movement transversely of the edge of the work and substantially in line with the awl when in position to penetrate the work. In the operation of the machine, the work is maintained against 45 the gage by the operator, and when the gage is moved forwardly, i. e. in the direction of the work, it necessarily thrusts the work forwardly. Consequently, forward movement of the gage is permitted only when the portion 50 of the work contacted by the gage is free to move. During the larger part of the cycle of operations of the machine, however such portion of the work is held against movement due to the work being clamped between the foot plate and the horn or to the

projection of the awl into the work in the path of movement of the gage. It is only during the relatively small part of the cycle of operations of the machine in which the awl passes through the final stage of its feeding movement after having been withdrawn from the path of movement of the gage that forward movement of the work and gage is allowed.

In the employment of the machine on many kinds of work, for example, in the manufacture of shoes of certain styles, it is necessary to move or adjust the gage during the operation of the machine on a single piece of work. The adjustment of the edge gage is effected without checking the operation of the machine, and has heretofore, so far as applicant is aware, been manually performed. Inasmuch as these machines operate very rapidly and the edge gage is capable of adjustment in the direction of the work during a small part only of the cycle of operations of the machine, the operator must act very quickly to effect complete adjustment of the gage at the desired point of the work. It results frequently that the operator effects only an incomplete adjustment of the gage in the short space of time permitted for the operation, thus causing uneven work.

In carrying out the objects of this invention, the above and other disadvantages attendant upon present methods of adjusting the edge gage have been obviated by the provision of improved power operated means for effecting the adjustment of the gage relatively to the plane of operation of the fastening inserting mechanism, so as to vary the distance by which the row of fastenings is spaced from the edge of the work. In the illustrated embodiment of the invention, the gage is moved both toward and from the plane of operation of the fastening inserting mechanism by power operated means, said means operating positively to move the gage away from the plane of operation of the fastening inserting mechanism and yielding through a spring to move the gage toward the plane of operation of the fastening inserting mechanism, the parts being so organized that, if it happens that the spring does not effect complete movement of the gage during the interval of the cycle of operations of the machine in which it is first made operative, the pressure of the

spring will be relieved from the work during the remainder of the cycle of operations, the spring being rendered operative on the gage, however, at intervals of the succeeding 5 cycles of operations, so that complete forward adjustment of the gage when once initiated is assured. The adjustment of the gage both toward and from the plane of operation of the fastening inserting mechanism is initiated by a manually controlled member operable at any time in the operation 10 of the machine to effect adjustment of the gage at the proper predetermined time in the cycle of operations of the machine.

15 In operating on certain classes of work it is particularly desirable to move the edge gage toward or from the plane of operation of the fastening inserting mechanism at the same time that a change is made in the 20 character of the fastenings inserted by the machine. For instance, it is common for the welt or outsole to be extended further out from the margin of the insole at the forepart of the shoe than in the shank, and 25 it is also desirable, by reason of the greater wear on the ball portion of the sole and the greater thickness of stock at the ball portion of the shoe and at the toe, to insert longer fastenings in the forepart than in the shank. Accordingly, another feature of 30 my invention resides in the provision of improved automatic means for moving the edge gage from one position of adjustment to another and also changing the character 35 of fastening inserted by the machine.

Although the embodiment of the invention now preferred by me is herein described and illustrated as applied to a machine for inserting string nails having an awl feed, 40 it is recognized that the invention is not restricted in its application to string nailing machines nor to machines characterized by an awl feed, but is capable of use with fastening inserting machines of other types. 45 Moreover, the invention in certain of its aspects is not restricted to the specific mechanism herein shown and described but is capable of embodiment in other forms without departing from the principles of the invention. It is therefore intended that the 50 scope of the invention shall be limited only as required by the claims.

Other objects and features of the invention will appear as the description proceeds 55 and will be pointed out in the appended claims.

In the drawings.

Figure 1 is a view in elevation of a fastening inserting machine with the invention applied thereto;

Fig. 2 is a view in elevation showing the power operated means for moving the edge gage to its different positions of adjustment; and

Fig. 3 is a view in detail of the connections

through which motion is transmitted to the edge gage.

The machine comprises a swinging head 2 carrying fastening inserting mechanism embodying a driver (not shown) and an awl 4. Motion is transmitted to the awl in a direction to cause the same to penetrate into the work by means of an arm 6, carrying a cam roll which engages a cam groove in the cam 8, the connections from the arm 6 to the awl being preferably of the character fully shown and described in the application of Fred L. Mackenzie, Serial No. 137,152, filed December 15, 1916. The head 2 is moved laterally during the time the awl 70 is in the work to effect feeding movement of the work by an arm 10 mounted on a shaft journaled in the frame of the machine, and actuated by an arm 12 controlled in its movements by the cam 8.

80 Means are provided for changing the character of the fastening inserted by the machine, as, for example, effectuating a change from shorter to longer fastenings or vice versa. Such means comprises an oscillating member 14 having impact surfaces 16 and 18 on opposite sides of its axis and an impact member in the form of a plunger 20, the path of movement of which is capable 85 of being changed, so that it may impart a blow against either of the impact surfaces 16 and 18 and thereby change the character of fastening inserted by the machine. The plunger 20 is connected to and operated from, the arm 6, and, inasmuch as the arm 90 95 effects the work penetrating movement of the awl, it will be understood from the foregoing that the oscillating member 14 is shifted simultaneously with the penetration 100 of the work by the awl 4.

In order to change the path of movement 105 of the plunger 20 and thus effect a change in the character of fastening being inserted, a bell-crank lever 22 is operatively connected to the plunger 20, said bell-crank lever being pivoted at 24 on a bracket 26 carried by a stud 28 fixed in the frame of the machine. The bell-crank lever 22 is connected to a link 30 pivoted at 32 on the bracket 26, said link 30 being provided with 110 a spring-pressed plunger (not shown) which operates to retain the bell-crank lever in position whether it be moved to cause the plunger 20 to align with the impact surface 16 or 18. By reference to Figs. 1 and 2, it 115 will be seen that when the bell-crank lever 22 is moved to align the plunger 20 with the impact surface 18 of the oscillating member 14, the connection between the bell-crank lever 22 and the link 30 is moved below the line of their pivotal points 24 and 32, whereas, when the bell-crank lever 22 is moved to align the plunger 20 with the impact surface 16, the point of connection between the bell-crank lever 22 and the link 30 is moved 120 125 130

above the line of their pivotal points 24 and 32, so that the spring-pressed plunger in the link 30 tends to maintain the bell-crank lever 22 in either of its operative positions.

5 A pin 33 is rigidly connected with the bell-crank lever 22 and limits the movement of such lever in a manner to cause the same to align with the impact surfaces 16 and 18 by engagement with the end walls of the recess 34 formed in a fixed part of the machine frame, as indicated in Fig. 2.

To the end of adapting the machine for the attachment of a welt to an upper and insole, the machine is equipped with a welt 15 guide 35 which delivers the welt in proper relation to the fastening inserting mechanism and the shoe. The machine is also provided with an edge gage 36 for positioning the work relatively to the fastening inserting mechanism and the welt guide and operating to guide the work in its movement past the fastening inserting mechanism.

The parts hereinbefore described do not in themselves form any part of the present invention, such parts being fully shown and described in the application of Fred L. MacKenzie, to which reference has heretofore been made. Further description of such parts is, therefore, deemed unnecessary.

30 In accordance with the invention, power-operated means are provided for moving the edge gage both toward and from the plane of operation of the fastening inserting mechanism, or, in other words, toward and from the edge of the work. As shown such means comprises a plunger 38 movable with the plunger 20, and means for transmitting the movement of the plunger 38 to the edge gage. In the illustrated embodiment of the invention, the means whereby the movement of the plunger 38 is transmitted to the edge gage 36 comprises a shaft 40 journaled in the bracket 26 and having laterally extended therefrom an arm 42

45 presenting an impact surface 44 in position to receive a blow from the plunger 38, and comprising further a spring 46 connected at one end to said arm and at the other end to a pin 47 carried by the bracket 26, and in 50 which a portion of the power exerted by the plunger 38 on the arm 44 is stored. The impact of the plunger 38 on the arm 42 moves the edge gage positively away from the plane of operation of the fastening inserting mechanism, whereas the spring 46 constitutes yielding means for moving the edge gage toward the plane of operation of the fastening inserting mechanism. It is desirable that the means for moving the edge gage

60 toward the plane of operation of the fastening inserting mechanism be yielding or non-positive in character as otherwise an excessive strain might be put on the awl. Inasmuch as the force of the spring 46 is 65 derived from the plunger 38, the gage 36

may properly be said to be power operated in both directions. The shaft 40 is connected by gearing 48 to a shaft 50 which is in turn geared to a rack formed in the upper surface of the shank 52 of the edge gage. 70 A spring 54, connected at one end to the shaft 50 and at its other end to a part of the machine frame, supplements the action of the spring 46 in moving the edge gage toward the plane of operation of the fastening inserting mechanism. 75

It will be understood from the foregoing that the bell-crank lever 22 may be moved at any time in the cycle of operations of the machine to align the plunger 38 with the impact surface 44 of the arm 42, whereby at a predetermined time in the cycle of operations of the machine the edge gage 36 will be moved away from the plane of operation of the fastening inserting mechanism. 80 To the end that the springs 46 and 54 may be rendered operative only when desired and at a predetermined time only in the cycle of operations of the machine, means is provided for normally maintaining the edge gage 85 against the action of said springs in the position to which it is moved by the action of the plunger 38 on the arm 42. Such means comprises a latch 56 formed with teeth arranged for engagement with complementary teeth 90 formed in the end of the arm 42, said latch being pivotally mounted on a bracket 58 carried by the stud 32 and being normally maintained in engagement with the teeth of the arm 42 by a spring 60. 100

In the operation of the machine as hereinbefore indicated, the work is normally clamped between a horn 62 and the foot plate of the machine, mechanism indicated at 64, Fig. 1, being provided for depressing the horn at periodic intervals to permit the work to be fed. The horn is maintained in raised position during the penetration of the work by the awl and is depressed immediately after the penetration of the work by the awl to permit the work to be fed relatively to the fastening inserting mechanism by lateral movement of the awl. Upon the completion of the feeding movement of the awl and as the awl is being withdrawn from the work, the horn is again raised to clamp the work against the foot plate of the machine and remains in clamping relation with the work during the operation of the driver and until the work is again penetrated by the awl. As hereinbefore indicated, the plunger 38 is moved downwardly to engage either with the impact surface 44 of the arm 42 or with the inclined surface 66 of the latch 56 simultaneously with the work penetrating movement of the awl. When it is desired to move the edge gage toward the plane of operation of the fastening inserting mechanism, the bell-crank lever 22 is swung to the right, Fig. 2, 115 120 125 130

whereby the plunger 38 is caused to engage with the inclined surface 66 of the latch 56 and free the edge gage from the restraint of said latch simultaneously with the penetration of the work by the awl. From the foregoing it will be understood that, as the horn is depressed and the work fed subsequent to the penetration of the work by the awl, the springs 46 and 54 are rendered operative to 5 thrust the edge gage 36 against the work and to push the work forward upon movement of the awl toward the line of drive of the fastenings. In the continuance of the operation of the machine, the plunger 38 is 10 raised from engagement with the latch 56 substantially simultaneously with the reclamping of the work between the horn and foot plate of the machine, whereupon the spring 60 presses the teeth of the latch 56 15 into engagement with the teeth of the arm 42. If it should occur that the springs 46 and 54 do not move the edge gage to its full limit of adjustment during the cycle of operations of the machine in which the springs 20 are first rendered operative to move the gage, the teeth of the latch 56 will engage the teeth of the member 42 upon the reclamping of the work between the horn 52 and the foot plate, and will thus release the work from 25 the pressure of the springs. Moreover, upon the next cycle of operations of the machine the plunger 38 will again engage the inclined surface 66 of the latch 56 and will render the springs 46 and 54 again operative 30 on the edge gage. It is thus manifest that when the adjustment of the edge gage is once initiated, the movement of the edge gage to its final limit of adjustment is assured.

In the foregoing specification, as also in 40 the appended claims, reference is sometimes made to the plane of operation of the fastening inserting mechanism. In the machine to which the invention is shown as applied, such plane of operation may be 45 taken as that passing through the awl and the driver. It is to be understood, however, that the invention is not limited to a machine having an awl feed and as applied to a machine which is not provided with an awl or 50 with feeding means of any nature, such plane is assumed to be substantially that passing through the line of drive of the fastenings and extending in the direction of the feeding movement of the work past the 55 edge gage and the driver.

Having described the invention, what I claim as new and desire to secure by Letters Patent of the United States is:

1. In a machine of the class described, 60 mechanism for inserting metallic fastenings, means for feeding the work relatively to the fastening inserting mechanism for the insertion of a row of fastenings in the work, a gage movable relatively to the plane of 65 operation of the fastening inserting mecha-

nism and constructed and arranged for engagement with the edge of the work, means for determining a plurality of positions of adjustment of the gage in each of which it will determine the spacing of a row of fastenings from the edge of the work, yielding means for moving the gage from one gaging position to another, means for retaining the gage in the first-mentioned position against the action of the yielding means, and 70 means operated in timed relation with the fastening inserting mechanism for moving the gage to one position of adjustment and operable to render the retaining means inoperative to allow the yielding means to move the gage to another position of adjustment. 75

2. In a machine of the class described, fastening inserting mechanism, a gage for positioning the work relatively to the fastening inserting mechanism, means for moving the gage relatively to the plane of operation of the fastening inserting mechanism, means for making the gage moving means normally inoperative, and power-operated 85 means normally operatively disconnected from said last-named means for rendering the gage moving means operative to move the gage. 90

3. In a machine of the class described, fastening inserting mechanism, a gage for positioning the work relatively to the fastening inserting mechanism, yielding means for moving the gage relatively to the plane of operation of the fastening inserting mechanism, and power-operated means for controlling the movement of the gage by said yielding means, said power operated means being normally operatively disconnected 100 from the gage and being constructed and arranged to adapt the gage to remain stationary during a plurality of cycles of operations of the machine. 105

4. In a machine of the class described, fastening inserting mechanism, a gage for positioning the work relatively to the fastening inserting mechanism, yielding means for moving the gage toward the plane of operation of the fastening inserting mechanism, means for retaining the gage against 110 movement by said yielding means, and operator controlled means for releasing the gage from the action of said retaining means at a predetermined time in the cycle of operations of the machine. 115

5. In a machine of the class described, fastening inserting mechanism, a gage for positioning the work relatively to the fastening inserting mechanism by engagement with the edge of the work, yielding means for 120 moving the gage in a direction to thrust the body of the work away from the plane of operation of the fastening inserting mechanism, a device operable to retain the gage against movement by said yielding means 125 130

- and movable bodily out of operative relation to the gage and means normally operatively disconnected from the retaining means and operated in timed relation with 5 the fastening inserting mechanism for releasing the gage from the action of the retaining means.
6. In a machine of the class described, fastening inserting mechanism, a gage member constructed and arranged to position the work relatively to the fastening inserting mechanism by engagement with the edge of the work, means for determining a plurality of positions of the gage member in each of 10 which it determines the spacing of a row of fastenings from the edge of the work, power operated means for controlling the movement of the gage to and from its positions of adjustment, and normally stationary 15 means movable by the operator at any time in the cycle of operations of the machine to render the power operated means operable to cause movement of the gage.
7. In a machine of the class described, fastening inserting mechanism, a gage constructed and arranged to position the work relatively to the fastening inserting mechanism, and a manually controlled power operated impact member for moving the gage 20 bodily at a predetermined time in the cycle of operations of the machine in a direction away from the plane of operation of the fastening inserting mechanism.
8. In a machine of the class described, mechanism for inserting metallic fastenings, 25 means for feeding the work relatively to the fastening inserting mechanism for the insertion of a row of fastenings in the work, a gage constructed and arranged to position the work relatively to the fastening inserting mechanism by engagement with the edge 30 of the work, a power-operated plunger normally operatively disconnected from the gage for automatically moving the gage 35 relatively to the plane of operation of the fastening inserting mechanism at a predetermined time only in the cycle of operations of the machine to vary the distance between the row of fastenings and the edge of the 40 work, and normally stationary operator-controlled means for rendering the plunger operative on the gage.
9. In a machine of the class described, fastening inserting mechanism, a gage for positioning the work relatively to the fastening inserting mechanism, means continuously tending to move the gage toward the plane of operation of the fastening inserting mechanism, and controlling means for said 45 gage moving means operating to make said gage moving means operative on the gage at predetermined times in successive cycles of operations of the machine and to render said gage moving means inoperative on 50 said gage at other times in the cycles of op- erations of the machine whereby complete movement of the gage is assured upon initiation of the operation of the gage moving means and the pressure of the gage on the work is relieved except at such times as 55 movement of the work and gage is permitted.
10. In a machine of the class described, fastening inserting mechanism, a gage for positioning the work relatively to the fastening inserting mechanism, means tending to move the gage toward the plane of operation of the fastening inserting mechanism, and operator controlled means for automatically rendering said gage moving 60 means alternately operative and inoperative.
11. In a machine of the class described, fastening inserting mechanism, a gage for positioning the work relatively to the fastening inserting mechanism, a spring for 65 moving the gage relatively to the plane of operation of the fastening inserting mechanism, a retainer for the gage, and means for automatically rendering the retainer inoperative on the gage to cause the spring to 70 move the gage at predetermined times in successive cycles of operations of the machine.
12. In a machine of the class described, fastening inserting mechanism, an awl for 75 feeding the work relatively to the fastening inserting mechanism for the insertion of a row of fastenings in the work, an edge gage constructed and arranged to guide the work as the work is fed past the gage, power op- 80 erated means for moving the gage in a direction away from the plane of operation of the fastening inserting mechanism and means tending to move the gage toward the plane of operation of the fastening inserting 85 mechanism.
13. In a machine of the class described, fastening inserting mechanism, means for feeding the work relatively to the fastening inserting mechanism for the insertion of a 90 row of fastenings in the work, a gage constructed and arranged to position the work relatively to the fastening inserting mechanism, yielding means for moving the gage in one direction, and power-operated mecha- 95 nism for moving the gage in the opposite direction and for rendering said yielding means operable to move the gage, said power-operated mechanism being normally 100 operatively disconnected from the gage.
14. In a machine of the class described, fastening inserting mechanism, an edge gage constructed and arranged to position the work relatively to the fastening inserting mechanism by engagement with the work 105 as the work is fed past the gage, an awl for feeding the work past the gage, yielding means for moving the gage toward the plane of operation of the fastening inserting mechanism, and power operated means for 110 115 120 125 130

moving the gage away from the plane of operation of the fastening inserting mechanism.

15. In a machine of the class described, fastening inserting mechanism, a gage constructed and arranged to position the work relatively to the fastening inserting mechanism, power operated means for moving the gage in one direction, yielding means for moving the gage in the opposite direction, and means controlled by said power-operated means for retaining the gage against movement by said yielding means.

16. In a machine of the class described, fastening inserting mechanism, a gage for 15 positioning the work relatively to the fastening inserting mechanism, power operated means for moving the gage in one direction, yielding means for moving the gage in the opposite direction, and means controlled by 20 said power operated means for retaining the gage against movement by said yielding means, said power operated means operating to move the gage at a predetermined time only in the cycle of operations of the machine and operating to permit movement of the gage by said yielding means at a predetermined time only in the cycle of operations of the machine.

17. In a machine of the class described, 30 fastening inserting mechanism, a gage for positioning the work relatively to the fastening inserting mechanism, power operated means constructed and arranged to move the gage in one direction at a predetermined time in the cycle of operations of the machine, yielding means tending to move the gage in the opposite direction, and a latch for retaining the gage against movement by said yielding means, said power operated 40 means being constructed and arranged to release the gage from retention by said latch at a predetermined time only in the cycle of operations of the machine.

18. In a machine of the class described, 45 fastening inserting mechanism, an edge gage for positioning the work relatively to the fastening inserting mechanism by engagement with the work to determine the spacing of a row of fastenings from the edge 50 of the work as the work is fed past the gage, an arm operatively connected to the gage, and a continuously reciprocating plunger arranged to impinge upon said arm thereby to move the edge gage.

55. 19. In a machine of the class described, fastening inserting mechanism, a gage for positioning the work relatively to the fastening inserting mechanism, an arm operatively connected to the gage, yielding means for 60 moving the gage, means for retaining the gage against movement by said yielding means, and power-operated means constructed and arranged to move the gage in one direction by operation on said arm and 65 to release said retaining means thereby to

permit movement of the gage in the opposite direction by said yielding means.

20. In a machine of the class described, fastening inserting mechanism, a gage for 70 positioning the work relatively to the fastening inserting mechanism, an arm operatively connected to the gage, yielding means for moving the gage, means for retaining the gage against movement by said yielding means, power-operated means constructed 75 and arranged to move the gage in one direction by operation on said arm and to release said retaining means thereby to permit movement of the gage in the opposite direction by said yielding means, and means for manually controlling the operation of said power-operated means.

21. In a machine of the class described, fastening inserting mechanism constructed and arranged to insert fastenings of varying 85 character, a gage for positioning the work relatively to the fastening inserting mechanism by engagement with the edge of the work, power operated means constructed and arranged upon change in 90 its path of movement to move the edge gage and change the character of fastening inserted by said mechanism, and means for changing the path of movement of the power operated means.

95 22. In a machine of the class described, fastening inserting mechanism constructed and arranged to insert fastenings of varying character, an edge gage member having a plurality of different operative positions 100 for positioning the work relatively to the fastening inserting mechanism by engagement with the edge of the work to determine the spacing of rows of fastenings at different distances from the edge of the work 105 as the work is fed past the gage, power operated means for automatically moving the edge gage away from the plane of operation of the fastening inserting mechanism and changing the character of fastening inserted by said mechanism.

110 23. In a machine of the class described, mechanism for inserting fastenings formed from wire comprising a wire guide, a gage for positioning the work relatively to the fastening inserting mechanism, by engagement with the edge of the work to determine the spacing of a row of fastenings from the edge of the work, and power operated means for automatically moving the edge gage to 115 determine the spacing of a row of fastenings at a different distance from the edge of the work, and for shifting the wire guide.

120 24. In a machine of the class described, fastening inserting mechanism constructed and arranged to insert fastenings of varying character, an oscillating member for controlling the character of fastening inserted by the fastening inserting mechanism, said member being provided with impact sur- 125 130

faces on opposite sides thereof, power-operated means operable to change the character of fastening inserted by the fastening inserting mechanism by oscillating said member through force exerted against one of said impact surfaces, a gage for positioning the work relatively to the fastening inserting mechanism by engagement with the edge of the work, and means movable with said power-operated means for controlling the movement of the edge gage.

25. In a machine of the class described, fastening inserting mechanism constructed and arranged to insert fastenings of varying character, an oscillating member for controlling the character of fastening inserted by the fastening inserting mechanism, said member being provided with impact surfaces on opposite sides thereof, a power operated plunger operable to change the character of fastening inserted by the fastening inserting mechanism by oscillating said member through force exerted against one of said impact surfaces, manually controlled means for changing the path of movement of said plunger to align with either of said impact surfaces, a gage for positioning the work relatively to the fastening inserting mechanism by engagement with the edge of the work, a member connected to the gage and operable to move the gage in one direction, means for controlling the movement of the gage in the opposite direction, and a plunger movable with the first-mentioned plunger and movable to operate on said member or upon said controlling means upon change in the path of movement of said plungers.

26. In a machine of the class described, fastening inserting mechanism constructed and arranged to insert fastenings of varying character, a gage member having a plurality of different operative positions for positioning the work relatively to the fastening inserting mechanism, power operated mechanism comprising a plurality of operating members joined together for movement as a unit, means operated by one of said operating members for changing the character of fastening inserted by said fastening inserting mechanism, and means operated by another of said members for moving the gage from one to another operative position.

27. In a machine of the class described, fastening inserting mechanism, a gage for positioning the work relatively to the fastening inserting mechanism, power operated means constructed and arranged for movement selectively in either of two paths in one of which it is operable to cause movement of the gage in one direction and in the other of which it is operable to cause movement of the gage in the opposite direction, and operator controlled means for changing

the path of movement of the power operated means.

28. In a machine of the class described, fastening inserting mechanism, a gage for positioning the work relatively to the fastening inserting mechanism, a power operated impact member constructed and arranged for movement selectively in either of two paths in one of which it is operable to cause movement of the gage in one direction and in the other of which it is operable to cause movement of the gage in the opposite direction, and manually controlled means for changing the path of movement of the impact member.

29. In a machine of the class described, fastening inserting mechanism, a gage for positioning the work relatively to the fastening inserting mechanism, yielding means for moving the gage toward the plane of operation of the fastening inserting mechanism, means for retaining the gage against movement by said yielding means, power operated means constructed and arranged for movement selectively in a plurality of paths in one of which it is operable to release the gage from the action of the retaining means, and means for changing the path of movement of said power operated means.

30. In a machine of the class described, fastening inserting mechanism comprising a foot-plate, work supporting means constructed and arranged to clamp the work against the foot-plate, an edge gage member having a plurality of different operative positions for positioning the work relatively to the fastening inserting mechanism by engagement with the edge of the work to determine the spacing of rows of fastenings at different distances from the edge of the work, means for moving the work support away from the foot-plate to release the work, an awl for feeding the work when thus released, yielding means for moving the gage toward the path of movement of the awl, and power-operated means for moving the gage away from the path of movement of the awl.

31. In a machine of the class described, fastening inserting mechanism constructed and arranged to insert fastenings of varying character, controlling means for the fastening inserting mechanism operable to cause a change in the character of fastening inserted by said mechanism, a gage for positioning the work relatively to the fastening inserting mechanism by engagement with the edge of the work, and power-operated means rendered operative by movement of said controlling means to effect movement of the gage from one gaging position to another.

32. In a machine of the class described, fastening inserting mechanism constructed and arranged to insert fastenings of vary-

- ing character, a gage for positioning the work relatively to the fastening inserting mechanism by engagement with the edge of the work, controlling means for effecting 5 movement of the gage from one gaging position to another, and power-operated means rendered operative by movement of the controlling means to change the character of fastenings inserted by said mechanism.
- 10 33. In a machine of the class described, fastening inserting mechanism constructed and arranged to insert fastenings of varying character, a gage for positioning the work relatively to the fastening inserting mechanism comprising a single gaging member having its bearing surface constantly in position to guide the work by engagement with the edge of the work during the insertion of fastenings of different characteristics, and 15 power-operated means for automatically moving the gage and changing the character of fastening inserted by said mechanism, said power-operated means being constructed and arranged to permit the gage to remain stationary during the successive insertion of a plurality of fastenings.
34. In a machine of the class described, fastening inserting mechanism constructed and arranged to insert fastenings of varying character, gaging means for positioning the work relatively to the fastening inserting mechanism, said means comprising a single gaging member having its bearing surface constantly in position to guide the work by 30 engagement with the edge of the work, power-operated means for automatically moving the gage from one guiding position to another and changing the character of fastening inserted by said mechanism, and 35 means for retaining the gage in either of its guiding positions.
35. In a machine of the class described, a horn adapted to enter and support a lasted upper and insole, means for feeding the work intermittently on the horn, fastening inserting mechanism for inserting fastenings intermediate between consecutive feeding movements of the work and constructed and 40 arranged to insert fastenings of varying character, a gage for guiding the work, as it is fed, by engagement with the edge of the work so as to position the work relatively to the fastening inserting mechanism after each feeding operation, power-operated 45 means for automatically moving the edge gage, means for changing the character of fastening inserted by said mechanism, and common controlling means for the power-operated means and the changing means.
- 50 36. In a machine of the class described, fastening inserting mechanism having means arranged to guide fastenings of different character to the inserting point, mechanism for shifting said means to change the 55 character of fastening inserted, controlling means for the shifting means, a gage for positioning the work relatively to the fastening inserting mechanism by engagement with the edge of the work, and power-operated means rendered operative by movement of the controlling means to effect movement of the gage from one gaging position to another concurrently with the shifting of the fastening guiding means.
37. In a machine of the class described, fastening inserting mechanism constructed and arranged to insert fastenings of varying character, means for changing the character of fastening inserted thereby, manual controlling means therefor, a gage operable to 70 position the work relatively to the fastening inserting mechanism by engagement with the edge of the work, power-operated means for moving the gage to different operative positions, and means operatively connected 75 with said manual controlling means for governing the operation of said power-operated means.
38. In a machine of the class described, fastening inserting mechanism constructed and arranged to insert fastenings of varying character, power-operated means for changing the character of fastening inserted thereby, controlling means for said power-operated means constructed for manipulation by 80 the operator, a gage operable to position the work relatively to the fastening inserting mechanism by engagement with the edge of the work, and means for moving the gage to different operative positions, said means 85 being governed in its operation by said controlling means.
39. In a machine of the class described, fastening inserting mechanism constructed and arranged to insert fastenings of varying character, a gage for positioning the work relatively to the fastening inserting mechanism by engagement with the edge of the work, and operator controlled power-operated means for automatically moving 90 the edge gage to another gaging position and changing the character of fastening inserted by said mechanism.
40. In a machine of the class described, fastening inserting mechanism constructed and arranged to insert fastenings of varying character, a gage movable between a plurality of operative positions for positioning the work relatively to the fastening inserting mechanism, operator controlled power-operated means comprising a plurality of 95 operating members, means operated by one of said operating members for changing the character of fastening inserted by said fastening inserting mechanism, and means operated by another of said members for moving the gage.
41. In a machine of the class described, fastening inserting mechanism constructed and arranged to insert fastenings of vary- 100

ing character, means for changing the character of fastening inserted by said fastening inserting mechanism, manual controlling means for said changing means, a gage 5 formed to present a bearing surface disposed adjacent to the fastening inserting mechanism and operable during the insertion of fastenings of different characteristics to position the work relatively to the fastening inserting mechanism by engagement 10 with the edge of the work, and power-operated means governed in its operation by said manual controlling means for effecting movement of the gage toward the plane 15 of operation of the fastening inserting mechanism.

42. In a machine of the class described, fastening inserting mechanism, a gage formed to present a bearing surface for engagement with the edge of the work as the work is moved past the fastening inserting mechanism, means for determining a plurality of positions of adjustment of the gage in each of which it will determine the spacing of a row of fastenings from the edge of the work, power-operated means for moving the gage from one position of adjustment to another, and means for retaining the gage in such last-named position 25 during a plurality of succeeding cycles of operation of the machine so that consecutively inserted fastenings are disposed in the same row.

43. In a machine of the class described, fastening inserting mechanism, a gage formed to present a bearing surface for engagement with the edge of the work as the work is moved past the fastening inserting mechanism, means for determining a plurality of positions of adjustment of the gage in each of which it will determine the spacing of a row of fastenings from the edge of the work, operator controlled power-operated means for moving the gage from one 30 position of adjustment to another, and means separate from the power-operated means for retaining the gage in such last-named position during a plurality of succeeding cycles of operation of the machine so that 35 consecutively inserted fastenings are disposed in the same row.

44. In a machine of the class described, fastening inserting mechanism, a gage formed to present a bearing surface for engagement with the edge of the work to position the work relatively to the fastening inserting mechanism, means for determining a plurality of positions of adjustment of the gage in each of which it will 40 determine the spacing of a row of fastenings from the edge of the work as the work is moved past the fastening inserting mechanism, power-operated means for moving the gage step by step from one of such positions of adjustment to another, means for 45

rendering the power-operated means inoperative on the gage, and means for effecting reverse movement of the gage.

45. In a machine of the class described, fastening inserting mechanism, means for 50 fastening the work relatively to the fastening inserting mechanism to cause the insertion of a row of fastenings in the work, a gage formed to present a bearing surface of engagement with the edge of the work 55 to determine the spacing of the row of fastenings from the edge of the work, means for positively moving the gage in one direction, means separate from the moving means for retaining the gage in the position to which it is thus moved, means for rendering the retaining means inoperative 60 to permit movement of the gage, and means for moving the gage in the opposite direction when the retaining means is rendered 65 inoperative.

46. In a machine of the class described, a work support constructed and arranged to support a shoe in inverted position, means for inserting metallic fastenings in the bottom of the shoe, means for feeding the work past the fastening inserting mechanism to cause the insertion of a row of fastenings in the work, a gage formed to present a bearing surface for engagement with the edge of 70 the work to determine the spacing of the row of fastenings from the edge of the work, and connections between the work feeding mechanisms and the gage constructed and arranged to move the gage to change the 75 spacing of the row of fastenings from the edge of the work.

47. In a machine of the class described, fastening inserting mechanism, an awl for feeding the work to cause the insertion of a 80 row of fastenings in the work, means for withdrawing the awl from the work upon the completion of the feeding of the work, a gage formed to present a bearing surface for engagement with the edge of the work 85 to determine the spacing of the row of fastenings from the edge of the work, and power-operated means for moving the gage toward the plane of operation of the fastening inserting mechanism during the feeding movement of the awl.

48. In a machine of the class described, fastening inserting mechanism, means for feeding the work relatively to the fastening inserting mechanism to cause the insertion 90 of a row of fastenings in the work, a gage formed to present a bearing surface for engagement with the edge of the work to determine the spacing of the row of fastenings from the edge of the work, power-operated 95 means for moving the gage in one direction, means separate from the power-operated means for retaining the gage in the position to which it is moved by the power-operated 100 means, operator controlled means for re- 105

- leasing the gage from the control of the retaining means, and means for effecting reverse movement of the gage when the gage is released from the retaining means.
- 5 49. In a machine of the class described, means for inserting metallic fastenings, an awl for feeding the work to cause the insertion of a row of fastenings in the work, mechanism for forcing the awl into the 10 work, a gage formed to present a bearing surface for engagement with the edge of the work to determine the spacing of the row of fastenings from the edge of the work, and connections between said mechanism and the gage constructed and arranged to move the gage to change the spacing of the row of fastenings from the edge of the work, said connections comprising an ele-
- 15

ment carried by and movable with said mechanism.

50. In a machine of the class described, fastening inserting mechanism, a gage formed to present a bearing surface for engagement with the edge of the work to position the work relatively to the fastening inserting mechanism, an awl for feeding the work, a lever for operating the awl, means carried by the lever for moving the gage in one direction relatively to the plane of operation of the fastening inserting mechanism, and yielding means for moving the gage in the opposite direction.

20 25 30
In testimony whereof I have signed my name to this specification.

FRED L. MACKENZIE.
